UNITED STATES PATENT OFFICE.

FITZ WILLIAM SARGENT, OF MAHWAH, NEW JERSEY, ASSIGNOR TO AMERICAN BRAKE SHOE & FOUNDRY COMPANY, OF MAHWAH, NEW JERSEY, A CORPORATION OF NEW JERSEY.

BACK FOR BRAKE-SHOES.

1,157,183.

Specification of Letters Patent. Patented Oct. 19, 1915.

Application filed July 27, 1915. Serial No. 42,137.

To all whom it may concern:

Be it known that I, FITZ WILLIAM SARGENT, a citizen of the United States, and a resident of Mahwah, in the county of Bergen and State of New Jersey, have made and invented certain new and useful Improvements in Backs for Brake-Shoes, of which the following is a specification.

This invention relates to a reinforcing back for brake shoes, and concerns in particular the securing of the wrought metal lug to the reinforcing back, the object of the invention being to accomplish the foregoing in such manner that the reinforcing back will not be weakened thereby, as has been the case when the transverse width of the central portion of the back has been reduced, in order that the ends of the lug could be bent therearound.

20 A further object is to offset the central portion of the reinforcing back, and against which the toes of the lug are bent, so that the latter do not extend to any considerable depth within the cast body of the shoe, allowing the same to be entirely worn away without the lug being cut or severed from the shoe.

25 A further object is to effect the securing of the lug to the steel back in such manner that the toes of the lug do not extend to any considerable distance in the body metal of the shoe, and to accomplish the foregoing without requiring other than a slight offsetting or crimping of the reinforcing back, and thus eliminating the possibilities of the reinforcing back becoming cracked or injured during the formation of such offset.

30 Other objects and advantages will appear as the description proceeds, wherein it is to be understood that changes in the precise embodiment of my invention can be made within the scope of what is claimed without departing from the spirit thereof.

45 The preferred embodiment of my invention is disclosed in the accompanying drawings, wherein:—

50 Figure 1 is a view in top plan of the reinforcing back prior to the attachment of the securing lug thereto; Fig. 2 is a view in side elevation of the reinforcing back and securing lug, embodying the characteristic features of my invention; Fig. 3 is a view in section of a brake shoe containing my

improved reinforcing back and securing lug, 55 the section being taken at the transverse median plane of the brake shoe; Fig. 4 is a fragmental view in perspective of the reinforcing back and the attaching lug.

Referring specifically to the several views, 60 the reinforcing back 5 is provided with the usual openings 6, for the reception of the cast metal of the body of the shoe, aiding in the secure anchorage of the reinforcing back to the body of the shoe.

65 The spacing of the sides of the lug of a brake shoe being fixed, and somewhat less than the width of the reinforcing back, it has been heretofore the practice to reduce the width of the central portion of the reinforcing back in order to receive the ends of the lug therearound, such practice resulting in the material weakening of the back, and in order to overcome this, and at the same time to obtain the proper spacing 70 of the sides of the lug, I provide the reinforcing back 5, which is of substantially uniform width throughout, with the longitudinally extending, and spaced, slits 7. These slits are spaced a distance from the side edges of the reinforcing back and are formed by the shearing of the metal of the back by the forcing upward, and offsetting, 75 of the central portion 8. As the central portion of the back is upwardly offset, the portions 9 of the back which lie to the sides of the slits 7, are downwardly offset to a distance approximately equal to, but opposite from, the upward offset of the central portion. The shearing and offsetting of the 80 portions of the back as thus outlined, results in the formation of the two spaced confronting openings 10.

85 The attaching lug 11, which is preferably formed of wrought metal, has the sides 12 bent through the confronting openings 10, and the toes 13 bent up into contact and engagement with the raised or upwardly offset portion 8 of the reinforcing back. The body 14 of the shoe is cast upon the 90 reinforcing back in the usual manner, and portions thereof flow up and around the sides of the wrought metal lug so as to reinforce and supplement the same.

100 The reinforcing back being of substantially uniform width throughout, is not in any wise weakened by the attachment of the securing lug, and the upward and down-

ward offsetting of the central and side portions of the reinforcing back, resulting, as it does, in the formation of confronting openings 10, reduces, and practically eliminates, the likelihood of the reinforcing back becoming fractured or injured by such formation, and as sometimes happens when the reinforcing back is upwardly bridged or offset only. The downward offset of the 10 sides of the back, and the slight protrusion of the toes of the lug below the general plane of the back do not interfere with, nor limit, the extent to which the brake shoe may be ordinarily worn.

15 What I claim is:—

1. A reinforcing back for brake shoes provided with spaced slits and with an offset portion thereintermediate, and a lug extending through said slits.
- 20 2. A reinforcing back for brake shoes provided with spaced slits, and with the portion therebetween offset and defining confronting openings, and a lug with the

sides thereof extending through said openings.

25 3. A reinforcing back for brake shoes provided with spaced slits with the sides thereof oppositely offset and defining confronting openings, and a lug with the sides extending through said openings and bent 30 into engagement with the lower surface of said back.

4. A reinforcing back for brake shoes provided with spaced slits, the portions of the back lying therebetween being upwardly 35 bent, and the portions lying to the sides of said slits being downwardly offset, and a lug with the ends thereof extending through said slits.

Signed at Mahwah, in the county of Bergen and State of New Jersey, this 17th day of July, A. D. 1915.

FITZ WILLIAM SARGENT.
